UNITED STATES PATENT OFFICE.

EDMOND QUILLET, OF VEVEY, SWITZERLAND.

BRICKMAKING MACHINE.

Application filed March 31, 1921. Serial No. 457,476.

To all whom it may concern:

Be it known that I, EDMOND QUILLET, architect, a citizen of Switzerland, residing at Vevey, Canton of Vaud, in the Confederation of Switzerland, have invented certain new and useful Improvements in or Relating to Brickmaking Machines (for which I have made applications for patents as follows: Switzerland, 18th January, 1918; 5 France, 15th January, 1919; Great Britain, 17th January, 1919; Belgium, 23rd January, 1919; Italy, 29th January, 1919; Spain, 11th February, 1919), of which the following is a specification.

15 The object of the invention is a machine for making bricks of compressible materials, in which two superposed plates are provided which are moved simultaneously so as to alternately move towards one another 20 or apart from one another, the lower plate bearing the portion of the mould in which the compressible material is placed and the upper plate bearing the pistons or the like intended to compress the said material.

25 The accompanying drawing shows, by way of example, one construction of the invention, intended to make several hollow bricks at a time.

Figure 1 is a side elevation of the machine, partially in section.

Figure 2 is a partial front elevation of Figure 1.

Figure 3 is a plan view, partially in section, of Figure 2.

35 Figure 4 shows at an enlarged scale, a portion of the movable parts of the machine.

40 Figure 5 is a plan view of one of the hollow bricks designed to be produced by the machine according to this invention.

45 Figure 6 is a plan view of three hollow bricks corresponding to the mould as shown in Figure 8 which is, with regard to the bricks, a section on the line A, A and B, B, of Figure 6.

Figure 7 is a partial section on the line A, A of the upper portion of one of the bricks of Figure 6.

50 Figure 8 is a similar section to the one of Figure 4 in which the movable parts of the machine are in another respective position.

55 Figure 9 is a similar section to the one of Figure 1 in which the movable parts of the machine are placed in a position corresponding to the wheels G having been turned

half a revolution from their position of Figure 2.

Figure 10 is a similar section showing the movable parts in a position corresponding to the wheels G having been turned three quarters of a revolution from the position shown in Figure 2.

Figures 11, 12 and 13 show in plan view, in a section on line D, D and in a section on line E E one of the removable plates O¹, which are placed at the bottom of the box D of the mould to form the cavities d and the projections c of the bricks a (see Figures 5 and 6.)

70 The frame of the machine is provided with pillars C which form the guides for the movable plates A and B, connected by means of connecting rods E to the crank pins F, of the wheels G. The latter are acted upon by means of pinions H the rotation of which is caused by the pulley L acting upon the endless worms K gearing with the worm wheels I fixed to the axles of the pinions H. A suitable hand lever (not shown) is provided for the purpose of putting the wheels G in or out of gear at will.

80 The plate B of the machine carries the box D of the mould in which a plate O (Figure 8) is arranged to which are affixed 85 the projections B¹ intended to form the outer shape and also the holes of the hollow bricks, as this may be seen by comparing the superposed parts in Figures 6 and 8.

90 Between the projections B¹ there are provided removable plates O¹ which are loosely laid upon the bottom plate of box D. The said removable plates O¹, shown in Figures 11 to 13, are intended to mould the holes d and projections c of the under face of the 95 bricks.

100 In the form as shown, the bricks are further to be provided with holes b each end of which is provided with a widening b¹ (Figure 7) intended to receive a plug connecting two adjacent bricks with one another. The widenings b¹ of the under face of the brick are formed by means of the projections n into which are screwed the rods N¹ intended to form the holes b.

105 The upper plate A is provided with projections A¹ intended to exactly fit between the projections B¹ of the lower plate. The said parts A¹ are further provided with projections n¹ intended to fit the rods N¹ and 110 to form the widenings b¹ of the upper face of the bricks.

- The extraction rods N fixed to the plate M pass through the plate B and the plate O (Figures 8 and 10) and they bear against the lower face of the removable plates O¹.
- 5 The plate M is fixed to a traverse M¹ which is capable of sliding along the rods P, fixed to the plate A and provided with a locking device intended to temporarily interlock the said traverse M¹ and the rods P.
- 10 The described machine works as follows: The parts being assumed to be in their respective position as shown in Figure 1, one fills the compressible material into the box D of the mould up to its top, as shown in Figure 8. Then one puts the wheels G into action thus causing the plates A and B to move towards each other until they reach their end position shown in the Figures 4 and 9.
- 15 20 In the position shown in Figures 4 and 9 the pistons A¹ have reached the position of the greatest compression of the brick, which position is also indicated in Figure 8 by dotted lines. The pistons being now 25 at the end of their stroke have completely formed the brick, the projections O¹ and n on plate o and the projections n' on the corresponding upper plate having produced 30 corresponding cavities therein.
- 25 30 The traverse M¹, by an automatic device not shown has now gripped the rods P, wherefore as the machine is continuing its movement and as the two plates A and B are beginning to retreat from each other, the plate M being coupled to the upper plate A will rise with the same, pushing thereby by means of the rods N, the plate O¹ with the compressed brick resting thereon, out of the descending mould D until the upper 35 edge of said mould has reached the level of the stationary table Z of the machine. At this stage of the working of the machine the brick has been completely cleared off the mould and is presented on the plate O¹ 40 ready to be removed by hand.
- 45 The machine is then stopped and the bricks are taken off together with their supporting plates O¹.
- 50 These plates O¹ are then replaced by similar ones and then, the locking connection between the traverse M¹ and the rods P is unlocked which causes the plate M and the rods N fixed to the same to fall down to their position of Figure 1, when the working 55 may begin again.
- Having now particularly described and ascertained the nature of my said invention and in what manner the same is to be performed, I declare that what I claim is:—
- 60 1. A machine for making hollow bricks of compressible material comprising an upper plate, a lower plate, means for simultaneously moving the said plates toward and away from each other, a mold carried 65 by the lower plate for receiving the ma-

terial to be compressed into bricks, and means cooperating with the upper plate in the separation thereof from the lower plate for removing the bricks from the said mold in which the same are formed.

70 2. A machine for making hollow bricks of compressible material, comprising an upper plate, a lower plate, a mold device carried by the lower plate for receiving the material from which the bricks are to be formed, means for moving the upper and lower plates toward and away from one another, means for forming a bore in each brick, and means cooperating with the upper plate when the same is separated from the lower plate for removing the bricks from the said mold device in which the same are formed.

75 3. A machine for making hollow bricks of compressible material comprising an upper plate, a lower plate, means for removing the said plates toward and away from each other, a mold device associated with the lower plate for receiving the material from which the bricks are to be made, auxiliary plates placed in the bottom of the 80 said mold device for forming grooves and depressions in corresponding faces of the bricks, and means cooperating with the upper plate when the said upper and lower plates are separated for moving the said auxiliary plates to remove the said bricks from the mold device.

85 4. A machine for making hollow bricks of compressible material comprising an upper plate, a lower plate, means for simultaneously moving the said plates toward and away from each other, a mold device carried by the lower plate for receiving the compressible material of which the bricks are to be made and in which the bricks are 90 formed, projections extending from the bottom of the mold device, rods projecting from the said projections whereby a bore with an enlarged end is made in each brick, and means cooperating with the upper plate when the same is separated from the lower plate for moving the bricks in the mold device.

95 5. A machine for making hollow bricks of compressible material comprising an upper plate, a lower plate, means for simultaneously moving the said plates toward and away from each other, a mold device carried by the lower plate for receiving the compressible material of which the bricks are to be made and in which the bricks are 100 formed, projections extending from the bottom of the mold device, rods projecting from the said projections whereby a bore with an enlarged end is made in each brick, auxiliary plates placed in the bottom of the 105 said mold device for forming recesses in corresponding faces of the said bricks, and devices cooperating with the upper plate when the same is separated from the lower plate 110 115 120 125 130

plate for raising the said auxiliary plates to remove the bricks from the said mold device.

6. A machine for making hollow bricks 5 of compressible material comprising an upper plate, a lower plate, means for simultaneously moving the said plates toward and away from each other, a mold device carried by the lower plate for receiving the 10 compressible material of which the bricks are to be made and in which the bricks are formed, projections extending from the bottom of the mold device, rods projecting from the said projections whereby a bore 15 with an enlarged end is made in each brick, auxiliary plates placed in the bottom of the said mold device for forming recesses in corresponding faces of the said bricks, a

transverse plate, a plurality of rods connected to the said transverse plate passing 20 through the bottom of the mold device and adapted to contact with the said auxiliary plates, and means for connecting the said transverse plate to the said upper plate so that when the upper plate is moved to separate the same from the lower plate the said transverse plate and plurality of rods are 25 actuated to raise the said auxiliary plates and thus lift the blocks from the mold device. 30

In testimony whereof I have affixed my signature in presence of two witnesses.

EDMOND QUILLET.
